will be made with the other two countries before the
January 1st, when each party will be in a position to
know what the other is doing and to take
the necessary steps to keep the peace. The
United States will do its best to help
the other two countries to do the same, and
we hope that the other two countries will
do the same for us.

UNITED STATES PATENT OFFICE

2,047,092

RADIO ANTENNA

Ira O. Banks, Higginsville, Mo.

Application September 5, 1933, Serial No. 688,224

1 Claim. (Cl. 250—33)

The invention relates to radio antenna and it is an object of the invention to provide a device for controlling the effective tone and volume of a radio receiver and to enable the operator to switch from an outside antenna to an inside antenna as desired.

Another object is to provide a device of novel construction and arrangement of parts, which may be easily connected to a radio receiver for effecting such switching operations, all of which will be hereinafter more fully described and claimed.

The present invention is an improvement over my patents for Radio antenna which issued June 13, 1933, as Patents No. 1,914,233, and No. 1,914,234, whereby some of the features of the two disclosures are incorporated with additional features as will be described hereinafter and having greater flexibility and other advantages.

Referring to the accompanying drawing which is made a part hereof and on which similar reference characters indicate similar parts.

Figure 1 is a diagrammatic view of the device connected to a radio receiver.

Figure 3 is an underside view of the device, showing the details of the resistor.

In the drawing numeral 10 indicates a casing provided with a flat plate resistor 11 mounted therein and having terminals 12 and 13 fixed to the ends thereof. A terminal 14 is provided intermediate the terminals 12 and 13 and is connected to a central shaft 15 having a moving contact 16 fixed thereto adapted to engage the plate resistor 11. The resistor is secured to the underside of the top of the housing 18 with the shaft 15 projecting therethrough. The shaft is provided with an operating knob 17 shown in dotted lines on Figure 2. A switch arm 19 is mounted on the shaft 15 beneath the knob 17 and is held in place by a nut 20 turned on the shaft.

The end 21 of the switch arm 19 extends outwardly from the knob and serves as an operating end and the other end 22 is adapted to engage contacts 23 and 24 positioned on the top of the casing and connected to the ends of the resistor plate 11. The movement of the arm is limited by the stops 25 and 26 fixed to contacts 23 and 24 respectively.

The terminals 12 and 13 are connected by wires 27 and 28 to the binding posts 29 and 30, respectively. The terminal 14 is connected by a wire 31 to the binding post 32.

PATENT OFFICE

, 1933, Serial No. 688,224
CL. 250—33)

Numeral 33 indicates a radio receiver provided with power input leads 34 and 35 connected thereto and antenna post 36 and ground post

37. An outside antenna 38 is connected to post 36 and to post 30 of the device by means of the wire 39. Post 32 is connected to ground wire 40 and post 29 is connected to ground post 37 of the radio receiver by wire 41. As shown an auxiliary lead 42 from outside antenna to one of the power input leads 34 is provided. A switch 43 and a condenser 44 are provided in the line 42, the purpose of this auxiliary lead 42 will be later described. The radio receiver 33 is also provided with blocking condensers 45 connected between the leads 34 and 35. A switch 46 is connected in the outside antenna circuit 38.

The operation of the device is as follows:

Considering the device connected as shown in Figure 1 where the radio receiver is grounded at 20 the power input side to the chassis or frame by using blocking condensers or where the electric house circuit is grounded it is advisable to use an auxiliary lead 42 to provide a power lead antenna circuit in any suitable manner; such a 25 circuit is diagrammatically indicated. The other end of the lead 42 is connected to the antenna post of the radio receiver.

By moving the switch arm 19 to contact the terminal 24, signals are received both on the outside antenna and the auxiliary line, the electric house circuit and the device which serves as an indoor antenna and controlled by the device. By moving the arm 16 along the resistor 11 the volume may be increased or decreased as desired. Should the signals to the radio receiver become noisy due to various disturbances transmitted by the outside or inside antenna this may be reduced by opening either the switch 43 in the auxiliary line or the switch 46 in the antenna 38. It is therefore possible to choose the antenna which will give the best signals. In either case the arm 16 may serve as a vernier when rotated on the resistor.

When the switch arm 19 is positioned between terminals 12 and 13, it would be necessary in order to obtain similar results to move the arm 16 to contact terminal 12, but the vernier effect of the arm 16 would be lost.

When the switch 19 is placed on contact 23, and switches 46 and 43 closed, the antenna and the receiver are grounded and the apparatus is protected against static or lightning discharges. By opening switch 46, the radio receiver receives signal energy from the power line through condens- 55

er 44. The volume is regulated by moving contact arm 16 on resistor 11 which is in series with the ground and the input circuit. With the switch 19 between contacts 23 and 24 and the switches 43 5 and 46 closed, the volume of the signals collected from the antenna 38 and the power line is varied by moving arm 16 over the resistor 11 which is now connected in shunt to the input circuit. By placing the arm 19 on contact 24, all of the resistance between contact 12 and the arm 16 is shorted, giving a different range of control.

The switch arm 19 when positioned intermediate the terminals 12 and 13 is non-effective. The arm 16 may be rotated to vary the potential drop 15 between the antenna post and ground post of the radio receiver to effect the volume of the signals to the radio receiver.

When it is desired to obtain signals by use of the outside antenna 38, the switch arm 19 is moved 20 to contact the terminal 12, this makes a direct ground from the ground post of the radio receiver to the outside ground and the signals are then controlled by movement of the arm 16 and the part of the resistance between the arm 16 and the 25 terminal 12 is non-effective, it being short circuited, the part adjacent the terminal 13 is effective to vary the signals to the radio receiver.

It may be seen that by using a device of the character above described, it is possible to vary 30 the volume of the signal by varying the potential drop across the antenna and ground post of the radio receiver and when desirable either the outside antenna or the indoor antenna may be used. The device permits switching from one to the 35 other in order to reduce static and other interferences which might be present or transmitted to

the radio receiver on one or the other of the antennae, in other words, the novel arrangement of parts and hook-up enables the operator to choose the circuit or antenna most desired for better reception and control of volume of signals received; to eliminate a part of the interference due to atmospheric conditions and to obtain results which might not otherwise be obtained unless the device is employed.

It will be obvious to those skilled in the art 10 that various changes may be made in my device without departing from the spirit of the invention and therefore I do not limit myself to what is shown in the drawing and described in the specification, but only as indicated by the appended 15 claim.

Having thus fully described my said invention, what I claim as new and desire to secure by Letters Patent, is:

A variable antenna control for the receiving 20 input circuit of a radio receiver having antenna and ground connecting means and an antenna connected to said antenna connecting means, said control comprising a resistance connected across said connecting means and having a grounded 25 contact engaging said resistance movable to vary the position of contact therewith, and a second movable grounded contact to be selectively connected with either end of said resistance or disconnected therefrom, whereby the first contact 30 may selectively vary the signal strength and whereby the operation of the second contact may selectively connect the antenna connecting means to ground, the ground connecting means to ground or leave both ungrounded thereby.
